UNITED STATES PATENT OFFICE.

JACOB TURNER, OF CHICAGO, ILLINOIS, ASSIGNOR TO TURNER MANUFACTURING COMPANY, OF CHICAGO, ILLINOIS, A CORPORATION OF ILLINOIS.

DESIGN FOR A MIRROR FRAME.

Application filed June 25, 1928. Serial No. 27,274. Term of patent 3½ years.

To all whom it may concern:

Be it known that I, JACOB TURNER, a citizen of the United States, residing at Chicago, in the county of Cook and State of Illinois, have invented a new, original, and ornamental Design for Mirror Frame, of which the following is a specification, reference being had to the accompanying drawing, forming a part thereof.

Figure 1 is a front elevational view, and Figure 2 is a side elevational view, of a mirror frame, showing my new design.

I claim:

The ornamental design for a mirror frame, as shown.

JACOB TURNER.
